UNITED STATES PATENT OFFICE.

CLARENCE W. PIPER, OF ST. PAUL, MINNESOTA, ASSIGNOR TO ADOLPH C. WILCKEN, OF ST. PAUL, MINNESOTA.

BED-SPRING.

1,332,682.

Specification of Letters Patent.

Patented Mar. 2, 1920.

Application filed April 4, 1917. Serial No. 159,800.

To all whom it may concern:

Be it known that I, CLARENCE W. PIPER, a citizen of the United States, residing at St. Paul, in the county of Ramsey and State 5 of Minnesota, have invented a new and useful Improvement in Bed-Springs, of which the following is a specification.

This invention relates to certain new and useful improvements in bed springs, the primary object being to provide an improved bed spring, which is light, durable, simple and economical in construction and very neat in appearance.

With these and other objects in view, my 15 invention comprises the features of construction and combination of parts herein-after particularly described and claimed.

In the accompanying drawing forming part of this specification, Figure 1 is a 20 plan of a detail of a bed spring constructed in accordance with my invention; Fig. 2 is a side elevation of that portion of the bed spring shown in Fig. 1; Fig. 3 is a plan of one of the wire loops employed in the construction illustrated in Fig. 1; Fig. 4 is a 25 plan of a detail of one of the wire loops illustrated in Fig. 3, and Fig. 5 is a plan of a detail of a bed spring illustrating an alternative construction.

Referring to the drawing let 2 and 3 indicate the head and foot bars and 4 one of the side bars of a bed frame, said head and foot bars being mounted upon the side bar by the usual metal fittings 5 and 6. These 35 parts specified assist in producing the usual bed frame, but it will be understood that this frame may be of any suitable construction and of any preferred size. Arranged between the head and foot bars is a wire 40 fabric A, which is composed of a group of wire loops 7, each loop being secured to the head and foot bars by the sets of helical springs 8 and 9. Each of said loops consists of a strand or a single piece of wire 45 having its ends meeting and secured together by means of a metal clip 10. The longitudinal sides of said loop are arranged parallel and one extremity of said loop having the clip 10 is secured by one of the 50 springs of the group 8 to the head bar 2 and the opposite extremity is secured by one of the springs of the group 9 to the end bar 3. The ends of the coil springs 8 and 9 which are not secured to the loops of the 55 fabric are passed through suitable openings

11 in the end bars 2 and 3 as shown. Thus the loops are held under suitable tension to form a mattress supporting fabric in the bed frame.

The sides of each loop are held spaced 60 apart in parallel relation by means of the spacing links 12, said spacing links being distanced apart at substantially even intervals and the adjacent sides of each pair of loops are secured together by the links 13, 65 said links 13 being also suitably distanced apart at even intervals. In this manner a bed fabric lying in a single plane is formed by the loops and links. The links 12 and 13 are distributed in staggered relation, so 70 as to distribute as evenly as possible, the links throughout the entire area of the fabric.

The main body portion of the fabric has the sides of each loop and the adjacent sides 75 of each pair of loops evenly distanced apart with all of said sides lying parallel. For the purpose of reinforcing the strength of the fabric adjacent each side of the bed frame, the sides of the loops are arranged 80 closer together in stepped relation as they approach the extreme side edge of the bed spring. In this manner the fabric is reinforced in strength, so as to prevent sagging or straining of the bed spring when in 85 service. The coil springs which support the main or body portion of the fabric are all of substantially the same strength but the springs which support the loops that are arranged closer together in stepped relation 90 as they approach the side edges of the fabric are likewise of greater strength in stepped relation approaching the extreme side edges of the bed spring. In this manner the bed spring maintains greater sup- 95 porting strength approaching the side edges thereof, than in the body portion thereof between the sides of the bed frame. It is also contemplated that all of the coil springs may be of the same or substantially the same 100 strength when desired.

An additional advantage derived by arranging the springs in stepped relation, that is closer and closer together as they approach the side edges of the fabric or mat 105 is to reduce the liability of a person rolling off of the bed. It is found in practice with my invention that the increasing strength of the fabric toward the side edges as explained above tends to prevent or limit the 110

rolling action of a person lying upon a mattress, which is supported upon the fabric. There is a rebounding action, which rolls the person back upon the main or body portion of the bed.

In the construction appearing in Fig. 5, my invention is shown applied to a "twin bed" structure, each set of loops B and C being provided with adjusting bars 14 of 10 usual construction whereby the tension of the coil springs 15 which anchor and support the loops 16 is adjustable so that one set of loops may be of greater spring tension than the other. The parting loop 17 between these sets of loops B and C is secured to the adjusting bars 14 by the coil spring 18 and an equalizing link 19. The outer side portions of the sets of loops are arranged with the sides of the loops closer 20 and closer together as in the preferred construction above described. Each of the strands of the loops in both constructions of my invention consists of a solid wire core 20 of suitable size having loosely entwined 25 thereabout spirally wound wires 21 whereby a finished construction is formed of large diameter and durable (see Fig. 4).

In accordance with the patent statutes I have described the principles of operation 30 of my invention, together with the apparatus which I now consider to represent the best embodiment thereof, but I desire to have it understood that the construction shown is only illustrative and that the invention can be carried out by other means 35 and applied to uses other than those above

set forth within the scope of the following claims.

Having described my invention, what I claim as new and desire to protect by Let- 40 ters Patent is:—

1. A bed spring comprising in combination with a bed frame, a group of wire loops having longitudinal strands arranged in a single plane parallel to each other and anchored under spring tension by their extremities to the ends of said frame, said strands being arranged with their sides successively stepped closer and closer apart approaching the sides of said frame, whereby 45 the spring tension of the loops is successively strengthened, and links secured to the sides of said loops at intervals spreading said sides of each loop apart and coupling the adjacent sides of said loops together. 50 55

2. A bed spring comprising a frame having end bars, a plurality of individual loops the sides of which are parallel and in a single plane, springs of substantially equal strength connecting the ends of said loops 60 to said end bars, and links secured to said loops at intervals, spreading the sides of each loop apart and coupling the adjacent sides of said loops together, the sides of said loops being successively reduced in distance 65 apart as they approach the extreme side edges of said bed springs, whereby the spring tension of the loops is strengthened approaching said side edges.

In testimony whereof, I have signed my 70 name to this specification.

CLARENCE W. PIPER.
